(57) **CLAIM**

The ornamental design for a flossing tool head, as shown and described.

DESCRIPTION

FIG. 1 is a perspective view of my new design for a flossing tool head which, as shown, is mounted on a handle for the flossing tool head;

FIG. 2 is a right side view of the flossing tool head shown in FIG. 1 and wherein the left side view of the flossing tool head is the mirror image of the right side view of FIG. 2; FIG. 3 is a bottom plan view of the flossing tool head of FIG. 1;

FIG. 4 is a top plan view of the flossing tool head of FIG. 1;

FIG. 5 is a front view of the flossing tool head of FIG. 1; and, FIG. 6 is a rear view of the flossing tool head of FIG. 1. The broken lines are shown for illustrative purposes only and form no part of the claimed design.
